UNITED STATES PATENT OFFICE.

OTTAR S. LEE, OF CHICAGO, ILLINOIS, ASSIGNOR TO NYE TOOL & MACHINE WORKS.

SECURING MEANS.

Application filed February 6, 1925. Serial No. 7,293.

My invention relates generally to securing means, for releasably securing an object, as for example, and more particularly, a vise, to a support, as for example, an upright post; and my objects, generally stated, are to provide a novel, simple and economical construction of securing means; to provide a construction whereby the parts thereof are held against accidental disengagement when the means are not in use and thus overcome the objection of loss, or misplacing, of the parts; to provide in a construction of securing means comprising a flexible element and a tauting means, for the shifting of the tauting means along the flexible element, whereby the tauting means may be applied in the most advantageous position to the support to which the object is to be secured; and other objects as will be manifest from the following description:

Referring to the accompanying drawings:

Figure 1 is a plan view of a vise equipped with my improved securing means, showing it secured to a post shown in plan; Fig. 2 is an enlarged view in side elevation of the tauting device forming a part of the securing means, showing it in position relative to the post of Fig. 1; and Fig. 3 is a section taken at the line 3-3 on Fig. 2 and viewed in the direction of the arrows.

In the accompanying drawings the securing means are shown, by way of one embodiment of my invention, of a form particularly suitable for use with a vise of the type shown in United States Letters Patent No. 1,517,010 granted to me November 25, 1924, and formed with oppositely directed hook-lugs 4 and 5 on its body-portion for adjustable attachment thereto of the flexible element of the securing means, though it is not to be understood from the showing herein made that I intend to limit my invention to its use with a vise either of this type, or construction.

The securing means shown comprises a chain 6 provided at its ends with hooks 7 and 8 adapted to be hooked over the lugs 4 and 5. In practice, however, where the support to which the vise is to be secured is of smaller cross-section than the largest support to which the vise may be secured, one of the hooks 7 or 8 would be attached to one of the lugs 4 or 5 and the chain would be hooked at one of its links over the other

of the lugs 4 or 5 to position the chain fairly snugly about the support.

The securing means also comprises a tauting-device shown as of the wedge-type and comprising a guide-member 9 in the form of a yoke providing the spaced arms 10 apertured at 11 to receive the chain 6 which extends sufficiently freely through the apertures 11 as to permit the member 9 to be freely moved along the chain, the outer face of the member 9 containing a vertical recess 12 having undercut-portions 13. The tauting means also comprises a wedge-member 14 presenting at one side a portion 15 at which it engages a side of the support to which the vise is to be secured and at its opposite side a portion 16 inclining relative to the portion 15 and provided with laterally-extending guide-flanges 17, this portion of the member 14 extending into the recess 12 with its flanges 17 extending guidingly into the undercut portions 13 of this recess. The wedge-member 14 is thus free to slide up and down on the member 9 and these parts are held against accidental disengagement from each other by ribs 18 at the thicker end of the member 14 and by deflecting the flanges 17 at the opposite end of the member 9, as represented at 19 of one of the flanges 17.

In the use of the structure the vise is applied to the support, shown at 20 to fit against it as shown in the drawing, and the chain 6 then hooked over the lugs 4 and 5 as shown, the wedge-member 14 being raised on the guide-member 9, and the vise properly clamped in place on the support 20 by driving the wedge-member 14 downwardly.

It will be noted in this connection that the guide-member 9 being freely adjustable along the chain 6 the tauting means may be caused to extend at any desired position relative to the support 19 to cause the wedging action to be exerted at the most advantageous point.

The hooks 7 and 8 on the ends of the chains are preferably of such size as to prevent them from passing through the apertures 11 in the guide-member 9, thus preventing separation of these parts of the structure.

It will thus be understood from the foregoing that all of the parts of the securing means are so interlocked as to prevent accidental disengagement of any thereof, but not

interfere with the desired relative movement thereof in the application of the device to a support, with the manifest great advantage.

5 While I have illustrated and described a particular construction I do not wish to be understood as intending to limit my invention thereto as the same may be variously modified and altered without departing from the spirit of my invention.

10 What I claim as new, and desire to secure by Letters Patent, is:

11 1. Securing means comprising a flexible member, a guide-member operatively and adjustably engaging said flexible member, a wedge slidably engaging said guide-member and means for preventing disengagement of said wedge-member from said guide-member and said guide-member from said flexible member.

15 2. An element of a securing means comprising a flexible member, a guide member containing an aperture through which said flexible member freely extends intermediate its ends to permit said guide-member to be movable therealong, means on the ends of said flexible member to prevent its separation from the guide-member, a wedge slidably engaging said guide member, and co-30 acting means on said wedge and guide-member to prevent their disengagement.

3. The combination of a vise having

attaching lugs for the ends of a securing chain, a securing chain engaging said lugs, a guide-member having an aperture through 35 which said chain freely passes intermediate its ends, end hooks on said chain of a size greater than the area of the aperture in the guide-member, a wedge-member engaging said guide-member, and co-acting means on 40 the wedge-member and guide-member preventing said wedge-member from disengaging from said guide-member.

4. The combination of a vise having 45 attaching lugs for the ends of a securing chain, a securing chain engaging said lugs, a guide-member having an aperture through which said chain freely passes whereby said 50 guide-member may be adjusted along said chain, said guide-member being provided with a wedge-receiving recess having under-cut portions, a wedge-member adapted to contact at one of its sides with the support to which the vise is to be secured and provided on its opposite sides with flanges adapted to 55 extend into the recess formed in the face of the guide-member, said flanges being deflected at their lower ends, and ribs at the opposite ends of said wedge-member whereby 60 said wedge-member is adapted for vertical movement on the guide member and is held from displacement therefrom.

OTTAR S. LEE.
